FLOWER VASE

Robert H. C. M. Daenen, Erembodegem, and Pieter K. J. De Coster, Aalst, Belgium, assignors to Dart Industries Inc., Los Angeles, Calif.

Filed July 29, 1974, Ser. No. 492,803

Term of patent 14 years

Int. Cl. D11—02

U.S. Cl. D35—3 R

FIG. 2

FIG. 1 is a side elevational view of a flower vase embodying our ornamental design;

FIG. 2 is a top plan view thereof; and

FIG. 3 is a bottom plan view thereof.

We claim:

The ornamental design for a flower vase, substantially as is shown.
